PRESSURE CONTAINER WITH REMOVABLE CLOSURE

Harold L. Parr, Moline, Ill., assignor to Parr Instrument Co., Moline, Ill., a corporation of Illinois

Application June 30, 1949, Serial No. 102,325

8 Claims. (Cl. 220—61)

1

The present invention relates generally to pressure containers such as, for example, calorimeters, oxygen bombs, reaction vessels and the like, and more particularly to removable closure means for retaining gases and fluids under extremely high pressures and temperatures within the containers. My invention relates to improvements in the closures disclosed in Patent No. 1,115,238 granted October 27, 1914 to S. W. Parr and in Patent No. 2,065,870 granted to me December 29, 1936.

Each of these patents discloses a vessel having a cover which is held in closed position by means of a flanged collar threaded on the end of the vessel. Although containers of this type have been used successfully for years, they are subject to the disadvantage that during disassembly of the closure the collar moves upwardly relative to the cover and may interfere with gauges, valves and pipe connections which are generally mounted on top of the cover and often overhang the sides of the vessel.

A primary object of my invention relates to the provision of a closure in which the securing parts are not required to move toward the fittings, etc., on the cover during disassembly and hence do not interfere therewith.

A related object relates to the provision of a removable closure in which the elements can be removed radially outwardly and downwardly away from the fittings on top of the cover instead of upwardly toward the fittings as was heretofore known to those skilled in the art.

Another object of my invention relates to the provision of a closure in which the necessity for close tolerances in the machining of the parts is obviated.

A further object relates to the provision of a closure which facilitates the opening or closing of the vessel while hot.

Still another object relates to the provision of a container with a removable closure which does not require threads on the container, which provides for easier cleaning of the vessel.

These and other objects and advantages will be apparent to those skilled in the art after a consideration of the following description, in which reference is had to the drawings appended hereto, in which

Figure 1 is an elevational view of a pressure container embodying the principles of my invention, a portion of which is shown in section taken along a line 1—1 in Figure 2.

Figure 2 is a top plan view of the container.

Figure 3 is a fragmentary sectional view taken along a line 3—3 in Figure 2.

2

Figure 4 is a top plan view of a modified form of the invention, the parts being shown in a loosened position.

Figure 5 is a view similar to Figure 4 but with the closure secured in pressure retaining condition.

Figure 6 is an elevational view showing another embodiment of the invention, a portion of the container being broken away along a line 6—6 in Figure 7.

Figure 7 is a top plan view of the embodiment shown in Figure 6.

Referring now to the drawings, and more particularly to Figures 1, 2 and 3, the pressure container comprises a generally cylindrical hollow member or vessel 10 having a closed bottom 11 and an open top which can be covered by a closure 12. The closure 12 comprises a cover 13 having an annular groove 14 in the bottom surface, inwardly of the outer edge, and an annular sealing element 15 of a suitable yielding material, preferably resilient, such as rubber, although other material such as copper, gold, or even annealed stainless steel can be used in the heavier assemblies. The upper edge of the vessel 10 is received within the groove 14 in contact with the sealing element 15. The groove 14 receives the upper edge of the vessel with a fairly close fit to protect the seal 15 from the heat and pressure of the gases in the vessel.

Rising from the center of the cover is a neck 16 having a passage 17 communicating with the interior of the vessel. This neck provides a connection between the interior of the vessel and the necessary supply line valve indicated by reference numeral 18 and other fittings such as a pipe 19 which might connect with a pressure gauge or other device used in oxygen bomb work, as is well known to those skilled in the art. These various fittings are not an essential part of the present invention, but are shown to demonstrate the fact that they overhang the outer side of the vessel.

The closure is secured in closed position by means of a split ring comprising a pair of annular segments 25, 26 positioned in peripheral relation around the cover 13. In the preferred embodiment illustrated, the split ring comprises two segments, each of which is semi-circular and has a first inwardly extending flange or shoulder 27 near the lower edge thereof and a second flange 28 spaced above the flange 27 and extending inwardly over the cover 13 in overlapping relation thereto and to the vessel 10 itself. The lower flange 27 is positioned normally to engage a downwardly facing peripheral shoulder 29 on

the vessel 10, spaced axially beneath the open top end thereof and formed integrally with the vessel.

Each of the segments 25, 26 is provided with a number of angularly spaced threaded elements in the form of set screws 30 disposed in threaded apertures 31 in the top flange 28. These set screws 30 are mounted on vertical axes and have rounded lower ends 32 positioned to bear upon a peripheral bearing ring 33, which is seated in a peripheral recess 34 in the upper edge of the cover 13. The ring 33 has a groove or depression 35 in the top face to receive the rounded ends 32 of the set screws 30. Each of the screws 30 has a hexagonal socket 36 adapted to receive a suitable tool for tightening and loosening the screws into and out of clamping relation against the bearing ring 33.

A removable continuous band 40 loosely encircles the segments 25, 26 and normally is in the form of a circular collar. It is provided with a pair of diametrically opposed set screws 41, 42 threaded into apertures 43 in the band 40 and having wedging elements in the form of conical inner ends 44 which are insertable in cooperative wedging elements in the form of recesses 45 in the adjacent edges of the annular segments 25, 26. Each set screw 41, 42 has sockets 46 similar to those 36 in the set screws 33, by means of which the screws 41, 42 can be screwed into wedging relation between the adjacent ends of the segments to spread the latter apart.

In assembling the bomb, the cover 13 and vessel 10 are brought together and the upper edge of the vessel is fitted into the groove 14 in contact with the sealing ring 15. The two semi-circular segments 25, 26 are then placed in position with the flange 27 under the shoulder 29 on the vessel. The band 40 is then slipped over the lower end of the vessel 10 and raised into position embracing the segments 25, 26, the set screws 41, 42 being retracted outwardly to clear the segments. Then the set screws 41, 42 are tightened into wedging relation in the recesses 45 between the ends of the segments, thus spreading the latter apart. As the screws 41, 42 are thus tightened, the band 40 is sprung into an elliptical shape as is evident in Figure 2, whereby the intermediate side portions of the band are drawn inwardly against the mid portions of the segments 25, 26 as indicated at 47, 48, respectively.

Hence, by tightening the set screws 41, 42, the adjacent ends of the segments are wedged apart to force the mid portions outwardly at 47, 48 and at the same time the springing of the band by tightening the screws 41, 42 draws the band inwardly against the segments at 47, 48, thus rigidifying the entire structure.

The set screws 30 are also tightened in their threaded apertures 31 to bear downwardly against the bearing ring 33 in the cover 13, thus acting to force the latter and the sealing ring 15 downwardly in pressure tight relation upon the upper edge of the vessel. The screws 30 react against the upper flange 28 of each segment, tending to raise the latter but prevented from doing so by contact between the shoulders 27, 29 on the segments and the vessel, respectively. It is preferable to tighten each of the several set screws 30, 41, 42 a little at a time, to tighten them equally, rather than to completely tighten each one before beginning on another.

By the above explained method, the closure is secured in pressure tight relation on the vessel. This construction illustrated in Figures 1, 2 and

3 is designed to withstand internal pressures in the order of two thousand pounds per square inch. It should be noted that internal pressure does not tend to loosen or disturb the closure securing means, nor does it tend to increase the stress in the band 40. Internal pressure tends to force the cover away from the vessel, which force is resisted by the tensile strength of the segments 25, 26. The segments are not forced radially outwardly, however.

To remove the closure, all set screws 30, 41, 42 are loosened, the band 40 dropped downwardly away from the segments, and the segments moved laterally away from the bomb to release the cover, without any interference with the fittings, valves or gauges which might be mounted on the cover. When the set screws 41, 42 are loose, the band 40 returns to a cylindrical form because of its resilience, thus providing adequate clearance around the segments, with the latter moved into contact with each other, to permit the band to be slipped down away from the segments 25, 26.

The container shown in plan view in Figures 4 and 5 is generally similar to that described above, but is designed for much higher internal pressures, in the order of six thousand pounds per square inch. The parts of this embodiment are given similar reference numerals, to which are added the letter *a*. It will be evident upon inspection that there are more set screws 30a for resisting the greater internal pressures and the screws are spaced closer together to better distribute the pressure against the top of the flange 28a. The fittings 13, 19 have been omitted from these views to expose the details of construction.

The removable band 40a is considerably heavier, thus eliminating the distortion of the band when the set screws 41a, 42a are tightened as shown in Figure 5. The band 40a is, therefore, in a substantially cylindrical shape at all times. The outer surface 50 of the segments 25a, 26a is formed on the same radius of curvature as the inner surface 51 of the band, so that when the closure is tightened, as in Figure 5, the surfaces contact each other throughout their areas. The segments 25a, 26a are made slightly less than 180° in arc, thereby leaving a gap 52 between adjacent ends of the segments when the latter are spread to engage the band surface 51. The outer surface 50 of each segment is chamfered near the two ends thereof, as illustrated at 53, to provide clearance between the segments and the band 40a when the segments are closed together as in Figure 4.

The method of installing and removing the closure in this embodiment is similar to that described in connection with the embodiment of Figures 1, 2 and 3.

Whereas the closures shown in Figures 1 through 5 embody the sealing arrangement shown in Patent No. 1,115,238, the third embodiment shown in Figures 6 and 7 employ the method of sealing disclosed in my prior Patent No. 2,065,870, but according to the present invention, the threads are entirely eliminated from the closure.

The cover 55 in this embodiment is adapted to slide into the open end of the vessel 56, which is enlarged to provide an inwardly tapering seat 57 spaced below the upper edge of the vessel. The cover 55 has a flange 58 which engages the seat 57 to close the vessel and support the cover. A peripheral recess 59 is provided around the upper edge of the cover 55 to receive a resilient sealing element or ring 60 between the cover and the inner wall of the vessel 56. The bottom of the

recessed portion 59 of the cover 55 is a conical surface, so that the resilient seal can be forced downwardly to provide a wedging action to effectively seal the space between the cover and vessel. A bearing ring 61 of metal is disposed within the recess 59 in contact with the top of the sealing ring 60 and extends above the edge of the vessel. The sealing ring 60 is protected from high temperatures in the vessel by the cover closing against the seat 57.

A split ring in the form of a pair of generally semi-circular segments 62, 63 are disposed in peripheral relation to embrace the upper portion of the vessel in a manner similar to the herein-before described embodiments. In this instance, however, each of the segments has an upper flange 66 overlapping the upper edge of the vessel 56 and also the bearing ring 61, and has a conical inner surface 67 which engages a cooperative conical top surface 68 on the bearing ring 61 to provide a wedging action tending to urge the ring 61 and sealing element 60 downwardly into the recess 59 when the segments 62, 63 are moved inwardly toward the vessel 56. This increases the pressure of the element 60 against the vessel and cover for resisting internal pressure within the vessel.

The segments 62, 63 have lower flanges 69 adapted to engage a peripheral, downwardly facing shoulder 70 formed integrally around the vessel as in the previously described embodiments. A removable band 71 is provided to embrace the segments 62, 63 to prevent their spreading and to retain them in closure securing position. In this embodiment, no set screws are required, for the inner surface 72 of the band 71 is conical converging upwardly, and the outer surface 73 of the segments is also conical and adapted to contact with the surface 72, whereby downward pressure on the band tends to force the segments 62, 63 inwardly. Thus, the conical surfaces 72, 73 comprise wedging elements cooperable to retain the segments 62, 63 in securing position.

This embodiment is assembled by dropping the cover 55 into seating relation with the conical seat 57. The sealing element 60 and bearing ring 61 are then set into the recess 59, after which the segments 62, 63 are brought together on opposite sides of the vessel. The band 71 is then pressed downwardly over the segments. High pressures in the vessel are resisted by the top flange 66 of the segments, the reaction of which is transmitted through the lower flange 69 to the shoulder 70. Inasmuch as the conical surfaces 67, 68 are nearly in a plane perpendicular to the axis of the vessel, the component of the force of pressure within the container is insufficient to overcome the frictional resistance of the band 71 on the segments.

The principles of my invention are not necessarily limited to closures for containers, for they may be employed in other situations for coupling two members rigidly together wherever threaded flanged collars are now employed, as on pipes or tubes.

I do not intend my invention to be limited to the particular details shown and described herein, except as set forth in the following claims.

I claim:

1. Closure securing means for a container having a normally open top, a removable closure therefor, and a downwardly facing shoulder disposed peripherally on said container adjacent the top thereof, said securing means comprising a peripherally extending member split generally axially and having a first inwardly extending

5 flange adapted to engage said shoulder and a second flange positioned to overlap said closure, a removable band adapted to be mounted on and to embrace said split member and a threaded element disposed in a threaded aperture in said band and having a tapered end positioned to enter into wedging engagement between adjacent ends of said peripherally extending split member to expand the latter within said band by turning said element in its threaded aperture.

2. Closure securing means for a generally cylindrical hollow member having an open end, a closure therefor, and a radial shoulder peripherally disposed adjacent said open end, said securing means comprising a split ring adapted to loosely encircle said member and having a first inwardly projecting flange positioned to engage said shoulder and a second inwardly projecting flange positioned to overlap said closure, a removable band embracing said split ring, and a threaded element disposed in a threaded aperture in said band and having a tapered end positioned to enter into wedging engagement between adjacent ends of said split ring to expand the latter within said band by turning said element in its threaded aperture.

3. For use with a generally cylindrical hollow member having an open end, a shoulder extending peripherally adjacent said end and facing in the opposite direction thereto, and a removable closure for said open end, the improvement comprising means for securing said closure to close said open end including a plurality of annular segments adapted to be positioned in peripheral relation to said end of said member, each of said segments having a pair of axially spaced inwardly extending flanges adapted to receive between them said shoulder and said closure, a removable band adapted to peripherally embrace said annular segments, and a plurality of set screws disposed in threaded apertures in said band and having tapered ends positioned to enter into wedging engagement between adjacent ends of said segments to expand the latter within said band by turning said screws in their threaded apertures.

4. A pressure container comprising in combination, a generally cylindrical vessel having an open top and a downwardly facing peripheral shoulder spaced beneath said top, a cover disposed over the opening of said vessel, sealing means between said cover and said vessel, a plurality of annular segments, each segment having a lower flange engaging said shoulder and an upper flange extending inwardly over said cover to hold said closure, said sealing means and said vessel in pressure retaining relation, a removable band embracing said segments, and a plurality of set screws disposed in threaded apertures in said band and having tapered ends positioned to enter into wedging engagement between adjacent ends of said segments to expand the latter within said band by turning said screws in their threaded apertures.

5. For use with a generally cylindrical hollow member having an open end, a shoulder extending peripherally adjacent said end and facing in the opposite direction thereto, and a removable closure overlying said open end, the improvement which comprises means for securing said closure over said end including a split ring adapted to loosely encircle said member and having a pair of axially spaced inwardly extending flanges adapted to receive between them said shoulder and said closure, a plurality of threaded

elements disposed in threaded apertures in one of said flanges and adapted to bear against said closure to force the latter into closed position on said member, a removable band embracing said split ring, and a threaded element disposed in a threaded aperture in said band and having a tapered end positioned to enter into wedging engagement between adjacent ends of said split ring to expand the latter within said band by turning said last mentioned element in its threaded aperture.

6. For use with a generally cylindrical hollow member having an open end, a shoulder extending peripherally adjacent said end and facing in the opposite direction thereto, and a removable closure overlying said open end, the improvement which comprises means for securing said closure over said end, including a plurality of annular segments adapted to be positioned in peripheral relation to the end of said member, each of said segments having a first inwardly extending flange adapted to engage said shoulder, a second flange positioned to overlap said closure and a plurality of threaded elements disposed in threaded apertures in said second flange and adapted to bear against said closure to force the latter into closed position on said member, a removable band adapted to peripherally embrace said annular segments, and a plurality of set screws disposed in threaded apertures in said band and having tapered ends positioned to enter into wedging engagement between adjacent ends of said segments to expand the latter within said band by turning said screws in their threaded apertures.

7. A pressure container comprising in combination, a generally cylindrical vessel having an open top and a downwardly facing peripheral shoulder spaced beneath said top, a cover disposed over the opening of said vessel, sealing means between said cover and said vessel, a plurality of annular segments, each segment having a lower flange engaging said shoulder and an upper flange extending inwardly over said cover, a plurality of axially positioned set screws disposed in threaded apertures in said upper flange and adapted to bear against said cover to hold said cover, said sealing means and said vessel in pressure retaining relation, a removable band embracing said seg-

ments, and a plurality of set screws disposed in threaded apertures in said band and having tapered ends positioned to enter into wedging engagement between adjacent ends of said segments to expand the latter within said band by turning said last-mentioned set screws in their threaded apertures.

8. A coupling for connecting a pair of generally cylindrical members, said coupling comprising a plurality of annular segments adapted to be positioned in peripheral relation to adjacent portions of said members, each of said segments having a pair of axially spaced inwardly extending flanges adapted to receive therebetween cooperative parts of said members, a removable band adapted to peripherally embrace said segments, and a plurality of set screws disposed in threaded apertures in said band and having tapered ends positioned to enter into wedging engagement between adjacent ends of said annular segments to expand the latter within said band by turning said screws in their threaded apertures.
